J. BERG,
LIFTING JACK.
APPLICATION FILED NOV. 27, 1920.

1,396,314.

Patented Nov. 8, 1921.

Inventor:
Joseph Berg,

By Chas. E. Riordan
Atty.

UNITED STATES PATENT OFFICE.

JOSEPH BERG, OF LITTLE ROCK, ARKANSAS.

LIFTING-JACK.

1,396,314.

Specification of Letters Patent. Patented Nov. 8, 1921.

Application filed November 27, 1920. Serial No. 426,677.

To all whom it may concern:

Be it known that I, JOSEPH BERG, a citizen of the United States, and a resident of Little Rock, in the county of Pulaski and 5 State of Arkansas, have invented new and useful Improvements in Lifting-Jacks, of which the following is a specification.

My invention relates to jacks for use by 10 automobilists in lifting an axle so that the wheel will be raised from the ground to permit a tire or the wheel to be changed or repaired.

The invention seeks to provide a device 15 for stated purpose which may be easily placed in operative position and manipulated without requiring the operator to get under the car or to be subjected to other inconvenience.

The invention also seeks to provide a jack 20 by the use of which the desired lifting action will be effected easily and quickly, and the invention further seeks to provide a device which, when not in use, may be easily stored in the tool box in a small space.

25 All these objects are attained in such a device as is illustrated in the accompanying drawings and the invention consists in certain novel features which will be hereinafter first fully described and then particularly 30 pointed out in the appended claims.

In the drawing, wherein corresponding numerals of reference are used to indicate corresponding parts in each of the several views—

35 Figure 1 is a sectional elevation of my improved jack, and

Fig. 2 is a detail elevation of the outer lifting screw.

In carrying out my invention, I employ a 40 hollow standard 1, having a relatively wide, solid base 2, so that it will rest firmly on the ground, without an excessive tendency to tilt and fall. The upper end of the standard is internally threaded as shown at 3, and a 45 lateral arm 4 extends from the standard near its upper end, said arm having an upturned extremity providing a bearing for the operating shaft or handle. It will be readily noted, upon reference to Fig. 1, that 50 the bearing is divided vertically so that the shaft may be inserted from the side thereby adding to the convenience of the device. Extending through and engaged in the internally threaded portion 3 of the standard 55 is the outer screw 5, which is hollow and

has an internally threaded head portion 6, which receives the externally threaded inner screw 7. Resting upon and fitting around the upper or head end of the standard is a bevel gear 8 having its hub portion 9 fitting 60 around the end or head of the outer screw. A feather 10 is secured in the hub 9 and engages a longitudinal groove 11 in the outer screw so that while rotation of the gear will effect rotation of the screw, the screw will be 65 permitted to move longitudinally by reason of its engagement with the head or nut portion 3 of the standard. One of the screws is right handed and the other is left handed and it will be readily noted that the threads 70 of the inner screw are coarser than those of the outer screw, so that a few turns of the outer screw will effect the desired elevation of the inner screw. It will also be noted that the inner screw will be set in motion 75 simultaneously with the outer screw so that the jack acts instantly, without any waste of time, and with the expenditure of slight effort. The inner screw is provided at its upper end with a fixed supporting head 12, and a restraining brace 13 is pivoted at one end to the said head and at its opposite end to a sleeve 14 fitted slidably on the operating shaft 15. The inner screw is thus held against turning and the entire force applied 80 to it is converted into longitudinal movement so that it is rapidly elevated. The operating shaft is provided at one end with a beveled pinion 16 meshing with the gear 8 and at the opposite end of the shaft is a 85 handle 17, whereby rotary motion may be imparted to the gear 8 in an obvious manner.

The operating shaft is composed of a plurality of sections detachably fitted together, 90 so that, when the device is not in use, the sections may be separated and fitted in the tool box so as to economize space therein. The handle is provided midway its ends with a socket 18 having a longitudinal slot 19 to 100 engage a stud 20 on the outer shaft section 21, which at its inner end is constructed with a longitudinal slot 22 to engage a stud 23 on the reduced outer end of the intermediate shaft section 24, said reduced end of section 105 24 fitting within the end of the section 21 as will be readily understood. The opposite end of the section 24 fits over the end of the gear carrying section 25 and is constructed with a longitudinal slot 26 to engage a stud 110

27 on the section 25. It will thus be seen that the sections of the shaft may be easily fitted together or separated and that when they are fitted together power may be applied to and through them positively.

5 It is to be particularly noted that the operating shaft and the restraining brace may be utilized as a handle device to place the jack under a vehicle and it is unnecessary 10 for the operator to get under the vehicle or to subject himself to any appreciable discomfort or inconvenience in order to bring the jack into the proper position for use.

15 The jack is very simple in construction and is direct and positive in action.

Having thus fully described my invention, what I claim as new and desire to secure by Letters Patent of the United States is—

20 1. A jack comprising a hollow standard having a lateral arm near its upper end, an outer screw mounted in the standard, an in-

ner screw mounted in the outer screw, a gear fitted around and supported by the upper end of the standard and connected with 25 the outer screw to rotate the same while permitting relative longitudinal movement thereof, an operating shaft mounted on the lateral arm of the standard and operatively connected to said gear, and a restraining 30 brace pivoted at one end to the head of the inner screw and having a slidable connection at its opposite end with the operating shaft.

2. A jack comprising a standard, inner 35 and outer screws mounted in said standard, gearing supported on the standard for operating said screws including a laterally extending shaft, a slidable sleeve on the said shaft, and a restraining brace pivoted at 40 one end to the head of the inner screw and at its opposite end to the said sleeve.

JOSEPH BERG.
